GEORGE M. CUSICK, OF GRAND RAPIDS, MICHIGAN

MAGNETO COUPLING

Application filed April 4, 1928. Serial No. 267,362.

This invention relates to a magneto coupling, and is particularly concerned with a novel form of coupling interposed between a magneto and a driving shaft therefor, the object and purpose of which is to automatically insure that the magneto armature shall be given a much higher speed of rotation than its driving shaft when said shaft is rotating at a low speed in order that the electromotive force developed by the magneto may be increased over what it would be if it was rotated with the same speed of rotation as the driving shaft therefor.

More specifically magnetos used to generate electric current for the ignition systems of internal combustion engines are in many respects ineffective in starting the engine either on manually cranking it or using a self starting mechanism, due to the fact that when the magneto armature is directly connected to its driving shaft it rotates at low speed and the spark produced is correspondingly weak. But with my invention it is designed that while the driving shaft for the magneto may be operated at the comparatively low speed at which it is turned either on cranking or by a self starter apparatus, use of the coupling of my invention causes the magneto armature to be checked and held against rotating during a part of the continuous rotation of the driving shaft therefor and then released and driven at a much higher speed of rotation than the driving shaft, such speed of rotation of the armature taking place at the proper times that the excess electromotive force developed may be used for the ignition spark of the ignition system of the engine with the result that a much larger and hotter spark is produced by the spark plugs in the cylinders of the engine.

My invention comprises many novel details of construction and arrangement of parts for very simply and effectively attaining the ends stated and for the production of a coupling which may be easily interposed between the magneto armature of the shaft driving the same. An understanding of the invention may be had from the following description taken in connection with the accompanying drawings, in which,

Fig. 1 is a side elevation showing the coupling of my invention interposed between a magneto and a driving shaft.

Fig. 2 is a vertical longitudinal section through said coupling.

Fig. 3 is a transverse vertical section substantially on the plane of line 3—3 of Fig. 2.

Fig. 4 is a section similar to that shown in Fig. 3 illustrating the coupling in another and different angular position of rotation.

Fig. 5 is a section similar to those shown in Figs. 3 and 4, the plane of the section however, being taken slightly to one side of the plane of the sections shown in Figs. 3 and 4, showing the operation of the coupling in the case of a backfire and a reversal of direction of turning.

Figs. 6 and 7 are perspective views illustrating different elements of the coupling construction.

Fig. 8 is a partial longitudinal vertical section and side elevation somewhat similar to the section shown in Fig. 2, but with the inner members of the coupling shown in side elevation, and

Fig. 9 is a transverse vertical section and end elevation of the coupling on the plane of line 9—9 of Fig. 8.

Like reference characters refer to like parts in the different figures of the drawings.

The magneto may be of any conventional construction having an outer housing or casting 1 within which the armature (not shown) is mounted for rotation on a shaft 2, the shaft extending beyond one end of the casting. On the end of the shaft the coupling of my invention is mounted.

In the construction of the coupling a bushing 3 of metal is permanently keyed at the end of the shaft 2 and adjacent the end nearest the magneto has an outwardly extending annular rib or flange 4 between which and the opposite end of the bushing 3 is a continuous annular recess 5. A cylindrical sleeve 6 surrounds the bushing and is connected thereto by means of a coiled torsion spring 7 housed within the annular groove or recess 5, one end of the spring having connection to said bushing and the other end being received in an opening in the sleeve 6, as shown in Fig.

2. The sleeve 6 is located within an outer cylinder 9 from which two spaced apart coupling jaws 10 project away from the magneto. The cylinder 9 is connected to the sleeve 6 by means of screws 11 threading through opposite sides of the cylinder 9, and at their inner ends having pins which may be received in anyone of a plurality of spaced apart openings 12 made around the sleeve. 5
- 10 By this means the sleeve 6 is rotatably adjustable relative to the driving member 9 and they may be fixed in any of a multiplicity of adjusted relations by insertion of the screws 11. This permits the magneto to be 15 accurately "timed" with the engine.
- At what may be termed its outer end the sleeve 6 is cut away at diametrically opposed points to make two elongated recesses 13 in the end of the sleeve. At the other end of 20 the sleeve it is provided with two diametrically opposed projections 14 one end of each being cut at an angle, as indicated at 15, to provide a cam on each projection 14, the purpose of which will hereafter appear.
- 25 A disc 16 is located over the shaft 2 at the inner end of the bushing 3. Two centrifugal wings 17 are located around the inner end of the bushing 3, being partly received in the annular groove made between the disc 16 and the flange 4, and being pivotally connected at one end by means of pivots 18 which extend through said disc and flange thereby attaching the disc 16 to the end of the bushing 3 and pivotally mounting 30 the wings 17 on the flange 4. Each of the centrifugal wings 17 at the side thereof nearest the magneto carries a lug 19 at its outer edge and substantially midway between its ends. Each of the wings 17 at its opposite 35 side and near its free end is equipped with a second lug 20. The lugs 20 lie in the same vertical plane as the flange 4 of the bushing 3. It is also evident that the projections 14 on sleeve 6 extend over said flange 4. The 40 bushing 3 at its end farthest away from the magneto is equipped with two projections 21 which in practice are screw heads which lie in the elongated recess 13 made in the sleeve 6 (see Fig. 8).
- 45 The jaws 10 of the cylinder 9 cooperate with similar jaws 22 and a coupling block 23 between the jaws for connecting the coupling construction described with a device 24 mounted on the driving shaft 25. The 50 construction housed within and associated with the device 24 is not illustrated or described as it has no bearing or effect with respect to the present invention, and so far as the present invention is concerned any suitable means of making a connection between the cylinder 9 and a drive shaft, such as the shaft 25 may be used.
- 55 In the operation of the coupling described, when the engine is running at low speed or 60 when it is being cranked or started with a

self starting apparatus, the shaft 25 turns at a low speed compared with what it does regularly during the operation of the engine. The rotation of the coupling member being in the direction indicated by the arrow in Fig. 3, it is evident that the uppermost wing 17 a short time prior to reaching the position shown in Fig. 3 drops by gravity to the lowest position it can assume. There is a projection 1^a, in practice a cap screw head, 70 extending from the magneto housing 1 which is located in the path of movement of the lugs 19 on the wings 17 when said wings are in the position shown in Fig. 3, and the lug 19 comes against the projection 1^a with the result that the bushing 3, shaft 2, wings 17 and the magneto armature are stopped from movement. The cylinder 10 and connected sleeve 6 continues rotating however, and the torsion spring 7 is stressed and wound and 75 stores considerable power.

80 Continued movement of the sleeve 6 brings the cam end 15 of one of the projections 14 to the lug 20 on the upper wing 17, as fully shown in Fig. 4 whereby the projection 14 rides underneath the lug 20, lifting lug 19 out of engagement with the stop 1^a, whereupon the power stored in the spring 7 acts 85 immediately to give the shaft 2 and its connected armature an immediate and strong impulse of rotation causing the armature to be rotated rapidly with a consequent development of a much greater electromotive force with a greater current to the ignition system and a more intense spark for firing the explosive charges in the cylinders.

90 It is of course to be understood, as has been mentioned before, that the timing of the explosions of the charges in the cylinders of the engine is such that the spark acts when the greater rotation of the armature of the magneto takes place. Should there be a reverse rotation of the drive shaft 25, due to engine backfire or any other cause, the wings 17 occupy positions such as shown in Fig. 5 and the lugs 19 will pass over the stop 1^a, because the wings 17 will not occupy their inner position by gravity until such time as a lug 19 has passed by the stop 1^a; but when rotated in the proper direction, the upper wing 17 drops to its lower or inner position before the lug 19 comes to the stop 1^a.

95 It is evident that the springs 7 may have any desired initial tension at the beginning. The screw heads 21 normally come against one end of the recesses 13, as shown in Fig. 8; and when the spring is being additionally tensioned during the operation of the device, the sleeve 6 turns while the screw heads 21 100 remain stationary thereby effecting a relative traverse of the recesses 13 by said screw heads. When the release is effected by a projection 14 riding under a lug 20 as described, the immediate and rapid rotary impulse given to the armature continues until 105

the screw heads 21 come against the ends of the recesses 13 or reach the position shown in Fig. 8.

The construction of coupling described is simple and easy to manufacture and may be readily assembled and installed. It is durable and efficient and has no parts liable to get out of order. As soon as the engine speed increases to a point where the rotation of the magneto armature is sufficient to produce the desired current, wings 17 are thrown outward by centrifugal force so that the lugs 19 pass over the stop 1^a. It is only at low engine speeds that the device is operative to cause the armature shaft to rotate faster than the shaft driving it at certain predetermined arcs of its rotation. This of course is a desirable feature of the invention as it is only at the low speeds that any increase of the electromotive force generated by the magneto is needed, while during the normal speeds of the engine, automatic ineffectiveness of operation of the device saves it from excess wear and consequent deterioration.

The invention is defined in the appended claims and is to be considered comprehensive of all forms of structure coming within their scope.

I claim:

1. A device of the class described comprising, a bushing adapted to be keyed to a magneto armature shaft and having a continuous annular groove around the same between its ends, a sleeve located around said bushing having two rows of spaced apart openings therearound, a coiled spring located within the groove of said bushing having one end attached to said sleeve, a coupling member located around said sleeve, means for connecting the coupling member to the sleeve comprising screws threading into said coupling member and having pins at their inner ends received in selected openings of the other of said rows of openings in said sleeve, said sleeve at one end having a plurality of projections, a plurality of centrifugal members pivotally connected to said bushing adjacent said projections, lugs one on each centrifugal member adjacent its free end and at the side thereof nearest said projections and under which said projections may pass on turning movement of the sleeve in one direction with respect to said bushing, and other lugs one on each centrifugal member projecting therefrom at the opposite side thereof between the ends of said members and near the outer edges thereof.

2. A device of the class described comprising, a driving member, a sleeve rotatably mounted on said driving member, means for adjustably fastening said sleeve to said driving member, a bushing adapted to be attached to a shaft, yieldable means connected to said sleeve and bushing to yieldably rotate the bushing by the sleeve, a centrifugal

member pivoted to said bushing, a stationary member engaged by said centrifugal member and means on said sleeve engageable with said centrifugal member upon rotation of said sleeve relative to said bushing to disengage the centrifugal member from the stationary member. 70

In testimony whereof I affix my signature.
GEORGE M. CUSICK.
